UNITED STATES PATENT OFFICE.

A. WASHBURN, OF MEDINA, AND T. BRINTNALL, OF YORK, OHIO.

IMPROVEMENT IN MACHINES FOR SHEARING SHEEP.

Specification forming part of Letters Patent No. **59,103**, dated October 23, 1866.

To all whom it may concern:

Be it known that we, ALVAH WASHBURN, of Medina, and THOMAS BRINTNALL, of York, in the county of Medina and State of Ohio, have invented a new and useful Improvement in Sheep-Shears; and we do hereby declare the following to be a full, clear, and exact description of the same, sufficient to enable one skilled in the art to which the invention appertains to make use of it, reference being had to the accompanying drawings, which form a part of this specification, and in which—

Figure 1 is a perspective view. Fig. 2 is a detached view of the shears and flexible attachment thereof to the tumbling-shaft.

The shears are provided with a shield over the cutters, to prevent the wool being cut more than once, and are attached by means of flexible connections and tumbling-rods to a counterbalance-arm, which is pivoted upon a standard, on which is placed the driving-wheel which gives the vibrating motion to the knife.

In the drawings, A is a base, which may be a removable board, a bench, or table, as may be convenient. From it rises a standard, B, which affords support for the axis C, which is common to the driving-wheel D and the counterbalance-arm E.

To the driving-wheel axis is attached the crank-handle F, and the motion of the driving-wheel is communicated to the smaller wheel G on the upper end of the arm E by means of a band or cord, H, which runs in grooves in the peripheries of the respective wheels.

The arm E is capable of motion in a vertical plane at the option of the shearer. The wheel being continuously turned by an assistant, the shearer draws down the end of the arm, so as to bring the shears to the convenient position for application on the animal.

To the axis of the wheel G is attached a flexible coupling, I, which, by means of the tumbling-rod J and flexible coupling K, is connected to the axis L of the crank M, by which the cutter-bar N is vibrated.

The cutter-bar N is pivoted in the case O, and vibrates between the guards P and shield R, Fig. 2.

The shears, as has been said, have a guard-plate, P, whose rear extension forms a bearing for the crank M, which operates the cutter-bar N. The forward end of the cutter-bar has teeth n, whose vibration forward and backward over the edges of the guards severs the wool which comes between them.

The wool when cut lies upon the shield, and is restrained from falling again into the jaws and being again cut and shortening the staple.

The weight of the shears is counterbalanced by the weight S, which is adjustable at the portion e of the arm E, being set at the required position by the set-screw e'.

The shield R is adjustable toward and from the points of the guards, and is attached by screws m to the guard-plate P, clips partially inclosing the boss on the rear of the guard-plate, and also its straight portion, as seen in Fig. 2.

To facilitate the withdrawal of the crank M its lower bearing is placed in a plate, p, which is unfastened by removing the screws s s.

Having described our invention, what we claim as new, and desire to secure by Letters Patent, is—

1. The swinging arm E, with a counterbalance-weight, substantially as described.
2. The shaft or tumbling-rod J, with flexible connections I K, operating substantially as described.
3. The adjustable shield R, covering the knives, and operating substantially as described.

ALVAH WASHBURN.
THOMAS BRINTNALL.
